(57) **CLAIM**

The ornamental design for a winged sofa with straight legs, as shown and described.

DESCRIPTION

FIG. 1 is a perspective view of a winged sofa with straight legs embodying the design in a first position;

FIG. 2 is a perspective view of the winged sofa with straight legs in a second position;

FIG. 3 is a perspective view of the winged sofa with straight legs in a third position;

FIG. 4 is a perspective view of the winged sofa with straight legs in a fourth position;

FIG. 5 is a perspective view of the winged sofa with straight legs in a fifth position;

FIG. 6 is a perspective view of the winged sofa with straight legs in a sixth position;

FIG. 7 is a perspective view of the winged sofa with straight legs in a seventh position;

FIG. 8 is a front view of the winged sofa with straight legs in first position;

FIG. 9 is a right side view of the winged sofa with straight legs in first position;

FIG. 10 is a left side view of the winged sofa with straight legs in first position;

FIG. 11 is a top view of the winged sofa with straight legs in first position;

FIG. 12 is a bottom view of the winged sofa with straight legs in first position; and,

FIG. 13 is a back view of the winged sofa with straight legs in first position.
